US0D1017817S

(12) **United States Design Patent** (10) **Patent No.:** **US D1,017,817 S**
(45) **Date of Patent:** **** Mar. 12, 2024**

(54) **PHYSIOTHERAPY LAMP HAT**

(71) Applicant: **DONGGUAN HUIFENG
TECHNOLOGY CO., LTD.,**
Dongguan (CN)

(72) Inventor: **Dezhao Xu**, Dongguan (CN)

(***) Term: **15 Years**

(21) Appl. No.: **29/824,935**

(22) Filed: **Jan. 27, 2022**

(51) LOC (14) Cl. **24-01**

(52) U.S. Cl.

USPC **D24/209**
